FIG. 1 is a top plan view of a combined measuring-sifter cup and wall mountable bracket therefor showing my new design.

FIG. 2 is a front elevational view of FIG. 1 wherein the bottom of the measuring-sifter cup is flat and unornamented.

FIG. 3 is a top plan view thereof, the sifter cap and over cap being removed and the handle being partially broken away for purposes of illustration.

FIG. 4 is an exploded perspective view of FIGS. 1 and 2.

FIG. 5 is a front elevational view of the wall mountable bracket.

FIG. 6 is an enlarged fragmentary cross-sectional view of the cover and sifter assembly, the view taken substantially along the line 6—6 of FIG. 1.

FIG. 7 is a rear elevational view of FIG. 2.

FIG. 8 is a side elevational view taken in the direction of line 8—8 of FIG. 7.

I claim:

The ornamental design for a combined measuring-sifter cup and wall mountable bracket therefor, as shown and described.
